(57) **CLAIM**

The ornamental design for a pet stroller as shown and described.

DESCRIPTION

FIG. 1 is a front elevational view of a pet stroller showing our new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a perspective view thereof;

FIG. 8 is a second perspective view thereof; and,

FIG. 9 is a third perspective view thereof.

The broken lines illustrate portions of the pet stroller that form no part of the claimed design.

1 Claim, 9 Drawing Sheets
